UNITED STATES PATENT OFFICE.

FRANCIS V. PHILLIPS, OF CHICAGO, ILL., ASSIGNOR TO MELVILLE E. DAYTON, OF SAME PLACE, AND GEORGE E. DAYTON, OF BURLINGTON, IOWA.

CONVERTIBLE STEP-LADDER.

SPECIFICATION forming part of Letters Patent No. 267,927, dated November 21, 1882.

Application filed November 30, 1881. (No model.)

To all whom it may concern:

Be it known that I, FRANCIS V. PHILLIPS, of Chicago, in the county of Cook and State of Illinois, have invented certain new and useful Improvements in Convertible Step-Ladders; and I do hereby declare that the following is a full, clear, and exact description thereof, reference being had to the accompanying drawings, and to the letters of reference marked thereon, which form a part of this specification.

This invention relates to a step-ladder constructed to be converted into a bench; and it consists in the matters hereinafter described and claimed.

In the drawings, Figure 1 is a perspective view of the device when extended to form a step-ladder, and Fig. 2 is a perspective view of the same folded to form a bench.

The same letter indicates the same part in both figures.

A A are parallel standards, to which are secured the steps A' A', in the usual manner.

B B are braces, pivoted to the standards A at the top through the medium of the brackets b b, and arranged in the same planes with said standards. Said braces B are connected by cross-rails B' B'.

C C are side bars, pivoted at one end externally to the braces B B at c c, and extending outside and beyond the standards A, where their opposite ends are connected by the cross-rod c'. When the parts are extended to form a step-ladder, as shown in Fig. 1, the connected bars C are raised until the cross-rod c' engages the projecting edge of the step A', in which position said bars C operate as a stop to prevent the feet of the standards and braces A and B from further spreading under the weight of a person. Notches cut in the edges 40 of the standards may serve the same purpose as the projecting edge of the step A'.

To adapt the step-ladder thus constructed to serve as a bench, legs D D, pivoted at d to the inner faces of the braces B, and pins a a, projecting from the outer faces of the standards A, are provided. Said pins a arrest the bars C in the inclined position shown in Fig. 2, wherein they form legs at one end of the bench. The pivoted legs D, connected by the 50 bar d' and notched at d', are made to rest upon

the back edge of a step, A', to support the free ends of the braces B, and with the step-standards A form legs at the other end of the bench.

Folded in the form shown in Fig. 2 the ladder constitutes a convenient bench for the support of a wash-tub, or for other uses. As a whole, therefore, the convertible step-ladder described serves particularly well as a convenient household article where both a bench and ladder are frequently required.

When not in use the standards and legs are folded together, as in other step-ladders, the legs D and bars C hanging down entirely out of the way.

To add to the usefulness of the article, both as a ladder for house-cleaning and as a wash-bench, the pivoted shelf E is applied, having the cleats e², pivoted to the inner face of the brackets b, or on the rod e³, which forms the 70 pivot of the braces B. The shelf E is upheld in the position shown in Fig. 1 by braces e, pivoted to the cleats e² at e', and notched at their lower ends to rest on the upper cross-rail, B'. When the ladder is transformed into a bench 75 the shelf lies in the position shown in Fig. 2, the ends thereof resting on the braces B.

Instead of the wooden brackets b, metal brackets may be used, furnishing connection, pivotal and otherwise, to the various parts joined 80 at the top of the ladder.

The bars C may have short pins or projections in place of the connecting-rod c', for the purpose of engaging the standards A, and the rod c' may be applied to connect the bars C at 85 the rear of the standards, or between said standards and the braces B; or, if preferred, a separate tie—as a strap—may be used to limit the spread of the standards and braces, and the bars C used merely as legs for the bench.

I have shown a series of holes, c², in the bars C, and one or more holes, a', in the standards A, by which, with the aid of a pin, the spread of the ladder may be varied at pleasure.

As a mere tie to hold the braces and standards from spreading, the bars C, pivoted to the braces, and arranged to engage the standards, as shown, may be employed on step-ladders not convertible, and for this purpose they may be pivoted to the standards and embrace or 100

engage the braces; or, in a convertible ladder for the purpose herein stated, said bars may be connected as last above described, and the legs D, also pivoted to the standards, being arranged to rest against the braces or a bar connecting them. In this case the standards and the steps will form the bench-top.

Of course, if desired, a board may be applied to the braces to give in the bench a continuous surface.

I claim as my invention—

1. In a step-ladder, the combination, with the step-standards A and pivoted braces B, of the pivoted bars C, stops a, and pivoted legs D, arranged and operating substantially as described, whereby the ladder is convertible into a bench, as set forth.

2. The convertible step-ladder and bench described, consisting of the step-standards A, having projecting steps A', the braces B, pivoted at the top of the standards, the bars C, pivoted to the braces, and provided with the connecting-rod c', arranged outside the standards, and the legs D, pivoted to the braces and notched at their lower ends to engage the rear edge of a step, A', substantially as and for the purposes set forth.

In testimony that I claim the foregoing as my invention I affix my signature in presence of two witnesses.

FRANCIS V. PHILLIPS.
